TRAY FOR A WRAPPED FRUIT CONTAINER

Joseph E. Murphy, Hicksville, and Murray Schnall, Brooklyn, N. Y., assignors to See-Qual Package Corp., New York, N. Y., a corporation of New York

Application October 16, 1952, Serial No. 21,856

Term of patent 14 years

(Cl. D58—26)

To all whom it may concern:

Be it known that we, Joseph E. Murphy and Murray Schnall, both citizens of the United States, residents, respectively, of Hicksville, county of Nassau, Long Island, State of New York, and Brooklyn, county of Kings, city and State of New York, have invented a new, original, and ornamental Design for a Tray for a Wrapped Fruit Container, of which the following is a specification, reference being had to the accompanying drawing, forming part hereof.

We claim:

The ornamental design for a tray for a wrapped fruit container, substantially as shown.

JOSEPH E. MURPHY.
MURRAY SCHNALL.
